UNITED STATES PATENT OFFICE.

FLOYD F. LIGHT, OF BECKLEY, WEST VIRGINIA.

BUCKET HANGER.

Application filed August 22, 1927. Serial No. 214,635.

This invention relates to an improved hanger or suspension device which is especially, but not necessarily, adapted for supporting a paint bucket on the building wall while painting to maintain the bucket in a convenient position to aid in the painting operation.

The most common type of paint bucket hangers are constructed to hang directly on the rungs of the ladder. However, owing to the different angles at which the ladder is tilted, the bucket is frequently in an out of the way position, thus hindering rapid work. In addition, the paint drips from the bucket in this position and accumulates on the ladder, making it disagreeable to handle in moving it from place to place.

What I propose is a simple and inexpensive article of manufacture which has been carefully designed with a view toward suspending the bucket directly from the building wall, particularly when the same is composed of weatherboard.

The features of construction of the improved hanger will become more readily apparent from the following description and drawings.

In the drawings:

Figure 1 is a perspective view of the hanger showing the manner in which it is supported, and the way in which the bucket is hung therefrom.

Figure 2 is a detail perspective view of the improved device.

In carrying out the invention, I provide what may be designated as a prop, indicated by the reference character 3. This comprises a substantially U-shaped length of wire whose bight portion is represented by the reference character 4 while the arms are indicated by the reference character 5. These arms are bent laterally and pointed to provide prongs as at 6 to be imbedded in the weatherboard 7, as shown in Figure 1. Rockably mounted on this prop is a frame-like member generally designated by the reference character 8. This is composed of a single length of wire which is bent to provide a pair of arms 9 terminating in angularly bent prongs 11, the latter being in-

tended to be wedged between the weatherboard as also shown in Figure 1. The intermediate portion of this part 8 is bent to provide eyes 11 which surround the bight portion 4 of the prop. The remainder is brought together and twisted as at 12 and then finally bent to form a suspension hook 13 for the bucket 14. The bail 15 of the bucket is simply engaged with the hook as shown in Figure 1.

A device of this kind is convenient, in that it can be readily placed in position to suspend the bucket within convenient reach of the ladder and yet entirely out of the way of the ladder. Not only this, the device is thought to be practical, dependable, and otherwise efficient. However, the exceptional simplicity renders the device capable of an easy understanding, for which reason a more detailed description is believed unnecessary.

Minor changes in shape, size and rearrangement of details may be resorted to within the scope of the adjoined claims.

I claim:

1. As a new product of manufacture, a bucket hanger of the class described comprising a frame-like member including a pair of spaced parallel arms terminating at one end in right-angularly bent anchoring prongs, having intermediate eyes, and provided at its opposite end with a suspension hook, and a substantially U-shaped prop, whose bight portion is extended through said eyes.

2. As a new product of manufacture, a frame-like suspension member composed of a single length of wire bent upon itself to provide a hook at one end, the portion of the wire inward of the hook being twisted together and formed with oppositely disposed eyes and terminating in spaced parallel arms whose extremities are bent to provide right-angularly disposed anchoring prongs, and a substantially U-shaped prop including arms terminating in prongs, the bight portion of said prop extending through said eyes.

In testimony whereof I affix my signature.

FLOYD F. LIGHT.
